UNITED STATES PATENT OFFICE.

ROBERT CHESTER WEISHAMPEL, OF BROOKLYN, NEW YORK.

HEATING APPARATUS.

1,373,110.

Specification of Letters Patent. Patented Mar. 29, 1921.

Application filed July 1, 1915. Serial No. 37,450.

To all whom it may concern:

Be it known that I, ROBERT CHESTER WEISHAMPEL, a citizen of the United States, residing at New York city, borough of Brooklyn, in the county of Kings and State of New York, have invented certain new and useful Improvements in Heating Apparatus, of which the following, taken in connection with the accompanying sheet of drawings, is

10 a full, clear, and concise description thereof.

The present invention is directed generally to improvements in heating devices and more especially to that class of heat devices commonly known as steam radiators for use in 15 heating the interior of buildings, vehicles and the like.

The object of the present invention is to provide a steam radiator which may be of a portable or stationary type, economically 20 constructed and adapted to operate with gas, oil or other suitable fuel.

A further object of my present invention is to provide a radiator directed to the attainment of the aforesaid objects, which will 25 also generate steam and have its coöperating parts so arranged that complete combustion of the fuel will be effected and the heat emanating therefrom will commingle with and be rendered moist or humid by the 30 steam generated in my improved radiator.

My invention further comprehends a structure of the aforesaid character, and embodying the feature of construction specified, in which will be incorporated means for automatically shutting off the fuel supply if 35 a radiator of the portable type should be accidentally upset, or upon the water from which the steam is generated reaching a dangerous or low level, and also in the latter 40 connection, where desired, in lieu of shutting off the fuel supply to automatically admit water to the radiator in such quantities as may be determined for effective operation.

45 My invention is further directed to a device designed to carry out the recited objects in an economical and efficient manner, wherein the circulation of the water within the radiator is so controlled and regulated 50 that steam may be created in a comparatively short period of time.

Other objects and advantages of my invention will become manifest as the description proceeds and I would have it distinctly understood that I do not limit myself to the 55 specific showing herein set forth or to the particular objects or functions recited, reserving unto myself the full range of equivalents and the various uses to which I am entitled within the spirit of my invention in 60 its broadest aspect.

I shall now proceed to describe my invention with reference to the accompanying drawings and then point out with more particularity the essential elements of nov- 65 elty therein, in the appended claims.

In the drawings, in which I have shown certain embodiments of my invention to render a clear and comprehensive understanding thereof,

70 Figure 1 is a view in perspective partly broken away to illustrate one form of my invention, which is a radiator operated by gas fuel design for interior purposes.

Fig. 2 is a detail of the damper employed 75 in the structure shown in Fig. 1.

Fig. 3 illustrates my invention as embodied in a stationary fixture, wherein the fuel is ignited by an electric spark and the water admitted to the tank automatically. 80

Referring now to the drawings in detail, in which like characters of reference are employed to designate similar parts throughout the several views, 7 indicates the outer casing, which may be made in any desirable 85 configuration of sheet or other suitable metal. This casing or tank may be of any size commensurate with the requirements to which the particular device is to be adapted and forms the water tank, being supported 90 upon the base 8, which is apertured at 9 to receive the pipe 10 extending upwardly therethrough to the end of which is connected the burner 11. It will be noted that by suitable connections the pipe 10 prefer- 95 ably extends upwardly along the exterior of one side of the casing 7 through the aperture 12 in the closure 13, the upper end of this pipe being provided with the controlling valve 14, the operation and function of 100 which will be hereinafter more fully explained.

Positioned within the tank or casing 7 is the combustion chamber 15, the base of which is apertured to receive the burner 11, the base of the combustion chamber 15 and the bottom of the tank or casing 7 having a joint formed at their apertured portions, so that the water in the tank 7 cannot enter the combustion chamber or pass through the aperture 9 and drip on to the surface 10 supporting the radiator.

It will be noted that the combustion chamber 15 in effect divides the tank into two sections of equal size, viz, A and B, the water in section A being forced through the pipe 16 passing through the combustion chamber in proximity to the burner 11, and discharging from the outlet 17 into the section B. Furthermore, effective circulation and rapid heating of the water is insured by reason of the fact that the exterior of the combustion chamber is of a slightly lesser transverse dimension, as shown at 15^a, than the interior width of the tank 7, thus forming a narrow passageway to permit the water 20 to completely surround and circulate about the combustion chamber. In assembling my structure with particular reference to the embodiment shown in Fig. 1, the upper end or mouth of the combustion chamber is 25 drawn against and rigidly secured to the wall of the tank 7 by means of the rivets or the like 18, the opposite side of the mouth of the combustion chamber being suitably connected to the opposite wall of the tank 30 to provide an elongated aperture or vent 19, the purpose of which will be hereinafter described.

By the construction thus far described, it will be obvious that when my improved radiator is in operation, the flame or fire from the burner 11 will surround the adjacent portion of the pipe 16 and impinge against the baffle plates 21 located within the combustion chamber 15 intermediate of the base 40 or mouth thereof and be deflected thereby, so that any remaining products of combustion will impinge against the oppositely positioned and angularly directed baffle plates 20, preferably formed integral with the closure or top 13 and insure complete 45 utilization of all of the heat units. The walls of the combustion chamber 15 become heated from the heat generated by the burner 11 and this heat is transmitted to the water and to the walls of the tank, and radiated therefrom to the atmosphere, the water circulating from the tank section A 50 through the pipe 16 to the tank section B and around the combustion chamber in the 55 aforesaid manner.

It will be noted that the tank as previously stated is divided into two sections A and B by the disposition of the combustion chamber 15 therein, the pipe 16 crossing 60 said chamber longitudinally and commun-

cating with each of the tank sections, the end of the pipe 16 indicated at 17^a in the tank section A being located below the water level, while the portion of the pipe located in the tank section B extends upwardly therein and terminates above the water level as shown at 17 in Fig. 1. By this arrangement, it will be manifest that the portion of the pipe 16 within the combustion chamber 15 will always contain water when 70 my device is in operative condition, this water being converted into vapor or steam by the heat generated by the burner 11 located in proximity thereto. This steam or vapor traversing the pipe 16 in the direction of 80 the tank section B and being condensed on its contact with the atmosphere within said section as it makes its exit from the pipe at 17.

Of course, it is obvious that by conduction from the heating of the wall of the combustion chamber that the body of the water within the tank would eventually reach the boiling point. This, however, would require a considerable amount 90 of time and result in the consumption of a large amount of fuel before the desired temperature is obtained. With my improved method, by the employment of the pipe 16 functioning as just described, the 95 upper surface of the water is heated almost immediately by reason of the fact that steam is created practically instantly within the pipe 16. This pipe may be said to be a heat distributing element which cooperates with the heat radiated by the walls of the combustion chamber to produce a boiling temperature within the water tank in from two to four minutes by reason of the fact that the hot water and steam expelled 100 therefrom being under pressure affects the entire area of the surface of the water to a like degree. Whereas, by depending solely upon conduction, as in the ordinary methods of heating, it would probably require 105 from fifteen to twenty minutes or more to heat the body of water within the device. It is evident that the products of combustion will issue from the mouth of the chamber 15, past the upper set of baffle plates 20, 110 while the steam generated within the tank will escape from the elongated opening or vent 19 and be deflected across the mouth of the combustion chamber by the deflector or hood 22, the steam commingling with the 115 products of combustion and producing a moist or humid atmosphere within the room or other place wherein my invention is used. The reference character 23 indicates a removable closure for the filler spout, through 120 which water may be conveyed to the tank 7.

As the steam is generated and the water level within the tank becomes low, in order to guard against accidents by reason of the tank becoming dry, I provide a float 125 130

connected by the chain 25 through the medium of a wire 26 to the rod or lever 27, whereby the valve 14 will be actuated upon the water reaching its low level to shut off 5 the fuel supply. When the supply of water has been replenished, the float will naturally rise and the valve may be manually opened by means of the pull chain or other means 28. To further increase the degree of 10 safety in the employment of the portable embodiment of my invention, I provide a spring 27^a connected to the rod or lever 27 and the closure 13, as shown in Fig. 1, which will operate to actuate the lever 27 and close 15 the valve should the apparatus be accidentally upset, the float 24 in such circumstances invariably shifting its position so that the chain 25 becomes slack and permits the spring to function. Under normal 20 conditions the weight 28^a fastened to the chain 28, renders the spring 27^a inoperative, but it is obvious that upon the radiator being upset the power of the weight, which is just sufficient to accomplish the result 25 mentioned and not interfere with the normal operation of the float control, will be negatived.

The closure 13 is preferably of the configuration shown and may be permanently 30 secured to the tank 7 in such a manner that a slot 22^a will be provided to the rear of the steam vent 19 to permit of the insertion of the apron 22^b of the hood or deflector 22, the latter being firmly supported in this 35 manner. The burner 11 is preferably of any well known Bunsen type and in order to admit sufficient oxygen thereto to render it effective under various conditions of use, I have found it expedient to provide a damper 40 29, such as shown in detail in Fig. 2, this damper being positioned in the side wall of the tank or casing 7 opposite the head of the burner.

In the embodiment of my invention shown 45 in Fig. 3, the principle of operation is substantially the same as that described with reference to Fig. 1, with the exception that the radiator is of the so-called stationary type, ignition of the fuel being effected by 50 an electric spark from the plugs 30, wired to a suitable source of supply, the circuit being established through the wires 31 and 32 by the operation of the switch 33. Furthermore, in this particular embodiment of my 55 invention the water is automatically admitted to the tank through the supply pipe 34, the nozzle thereof extending downwardly through the closure or top 13 of the radiator and being provided with a valve 35, which is normally held on its seat by the spring 36. When the water level falls 60 below normal, the valve 35 is opened by the settling of the float 37 which exerts a downward pull on the chain 38 against the tension 65 of the spring 36. As soon as the water level

returns to normal, it is manifest that the raising of the float will permit the spring 36 to function and return the valve 25 to its seat shutting off the water supply.

As is generally known, the ideal and 70 healthful heated atmosphere is one which contains a certain percentage of moisture and the objection heretofore made to gas and similar fuel heaters has been that they radiated an absolutely dry heat which in 75 many instances seriously affected the mucous membrane of the occupants of the room in which the heater was used, causing diseases of the head and throat. These present forms of heaters are also objectionable 80 owing to the incomplete combustion which makes an unpleasant odor about the premises, where they are employed. My invention it is manifest overcomes all of these objectionable features of the present day 85 heater by reason of the steam commingling with the products of combustion which not only provide the desirable moisture or humid atmosphere, but eliminates any possible objectionable odor by the filtration of 90 the products of combustion through the steam. Furthermore, by reason of its construction, it may be readily adapted for use with artificial or natural gas, or oil fuel.

It is, of course, obvious that the relative 95 arrangement of the combustion chamber and water tank and the proportions thereof may be varied to suit different requirements of use or design and that the details of structure and arrangement of the coöperating 100 elements may be changed without departing from the spirit and scope of my invention.

Having thus described my invention what I claim as new herein and desire to secure by Letters Patent is:

1. A radiator for heating a room or the like, comprising a water containing tank, a combustion chamber located therein intermediately of the ends thereof and dividing said tank into two relatively large sections, 110 the front and rear walls of said chamber being spaced from the adjacent walls of said tank to form a relatively narrow passageway and permit free circulation of the water about said chamber, a pipe passing 115 through said chamber, one end thereof being positioned below the water level in one tank section and the other end being above the water level in the other tank section, and means located in said combustion chamber 120 for heating a portion of said pipe therein, whereby a forced circulation of the water is set up through said pipe and from one tank section to the other.

2. A radiator for heating a room or the 125 like, comprising a water tank, a combustion chamber open at the top located therein and dividing the tank into two sections, a relatively narrow passageway being provided between the front and rear walls of 130

said chamber and the adjacent walls of said tank to permit free circulation of the water about said chamber; a pipe passing through 5 of said tank sections, means for heating said combustion chamber and a portion of said pipe therein to produce circulation of the

water through said pipe and within said tank and a steam vent in said tank in proximity to the top of said chamber whereby the products of combustion issuing therefrom and the steam will commingle to provide a moist heated atmosphere.

ROBERT CHESTER WEISHAMPEL.
